REVERSIBLE WINDOW HINGE

Filed July 23, 1931

UNITED STATES PATENT OFFICE

STANLEY H. BREWER, OF DUNDALK, MARYLAND

REVERSIBLE WINDOW HINGE

Application filed July 23, 1931. Serial No. 552,603.

This invention relates to windows and has special reference to a reversible window sash.

Window sashes have been constructed to swing on arm pivoted centrally of the top and bottom rails of the sash before the present invention, this arrangement facilitating the cleaning of the window by enabling the sash to be reversed in position so that the normal outer surface is faced into the building in which the window is located and is accessible for washing and polishing. However, such windows are not arranged so that they may be closed and latched with either side out but are so arranged that after the outside is cleaned the sash must be again reversed before closing. This makes it inconvenient to clean the sash on the outside in cold or stormy weather since, with the usual construction the sash must be at least partly open during the cleaning of the outside.

One important object of the invention is to provide an improved form of window sash arranged so that it may be closed with either side out.

A second important object of the invention is to provide an improved and novel latching means for such a sash, the latching means being operable from the inside no matter which side of the sash is outermost.

A third important object of the invention is to provide a novel arrangement of hinge for such a sash.

With the above and other objects in view as will be hereinafter apparent, the invention consists in general of certain novel details of construction and combinations of parts hereinafter fully described, illustrated in the accompanying drawing and specifically claimed.

In the accompanying drawing like characters of reference indicate like parts in the several views, and:

Figure 1 is an inside elevation, partly in section, of a window constructed in accordance with this invention.

Figure 2 is a section on the line 2—2 of Figure 1.

Figure 3 is a plan view of the improved device.

Figure 4 is a perspective view of a portion of the hinge used herewith.

In the embodiment here illustrated the invention is shown as applied to a double window but it is to be understood that the invention may equally well be used in connection with a single window or any other arrangement found convenient.

In this embodiment there is provided a window frame having a sill 10, a lintel 11 and vertical members 12, one of which here forms a center style. For each of the spaces thus formed there is provided a sash having a bottom member 13, a top member 14 and side members 15 alike on both sides so that the sash may fit the frame with either side outermost.

To the upper and lower corners of the frame are secured the hinge plates 16 each having a barrel 17, the barrel on each upper plate being aligned with the barrel on the respective lower plate. Through each pair of aligned barrels extends a hinge rod or pintle 18 and a spacer sleeve 19 is fitted on the pintle 18 between its barrels 17 so that the latter are kept in proper spaced relation.

This sleeve is fixed to its pintle by pins 20 so as to revolve therewith, the pintle itself revolving freely in its barrels. At the top and bottom the pintle projects beyond the barrels and on these projecting portions are mounted the barrels 21 of hinge arms 22, these barrels being fixed to the pintle by pins 23 so that the arms 22 are forced to swing in unison. Each arm 22 has a lip 24 projecting from the free end of the arm at right angles thereto and pivoted to each lip is a hinge plate 25 countersunk into the respective top and bottom sash member, the pivot 26 being located centrally of the said member.

Thus a sash may be reversed and will fit the frame in either position. Recesses 27 are provided in the members 10 and 11 to accommodate the hinge arms.

For each sash there is provided on each member 15 a latch 28 having an operating handle 29 on each face of the sash, these

latches being directly opposite each other and at each side of each sash space in the frame there is provided a keeper for the latch. These keepers are so arranged as to 5 be engaged by the respective latches no matter which face of the sash is outward.

By this means the sash may be closed with either side outermost and may be latched in closed position.

10 There has thus been provided a simple and efficient device of the kind described and for the purpose specified.

It is obvious that minor changes may be made in the form and construction of the 15 invention without departing from the material spirit thereof. It is not, therefore, desired to confine the invention to the exact form herein shown and described, but it is desired to include all such as properly come 20 within the scope claimed.

Having thus described the invention, what is claimed as new, is:

A hinge for use with swinging sashes, comprising upper and lower hinge plates 25 to be secured adjacent to a window opening, a vertical barrel forming a part of each plate, a pintle extending through the barrels, the ends of the pintle being extended beyond the ends of the barrels, a spacer sleeve 30 contacting with the adjacent ends of the barrels, and positioned on the pintle, means for securing the spacer sleeve to the pintle, sash engaging arms, barrels at the inner ends of the arms and fitted over the extended ends 35 of the pintle, means for securing the arms to the pintle and pivoted members at the free ends of the arms for securing the hinge to a window sash.

40 In testimony whereof I affix my signature.

STANLEY H. BREWER.
